WEFT REPLENISHING LOOM

Ernest A. Morin and Morris Bornstein, St. Hyacinthe, Quebec, Canada, assignors to Consolidated Silk Mills, Ltd., Montreal, Quebec, Canada

Application September 4, 1937, Serial No. 162,492

5 Claims. (Cl. 139—232)

This invention relates to looms and more particularly to looms for automatically replacing a depleted shuttle with a full one.

Looms have been provided with means for automatically replenishing the weft threads but heretofore these have been usually designed to accomplish this function without cessation of the weaving function. When it is borne in mind that the shuttle of a loom is approximately 15" long, 10 weighs about $\frac{3}{4}$ lb., and is projected from side to side of the loom at the rate of 141 times a minute, it is apparent that the replacing of a shuttle "on the fly" and within a time period of approximately $\frac{1}{3}$ second would be the source of considerable trouble, causing breakage, thereby entailing undue loss of time and money.

Realizing the advantages of automatically replenishing the weft, the invention seeks to provide a mechanism which, although automatic in 20 its function, stops the weaving operation while the change in shuttles is being made.

The invention therefore has for its primary object the provision of a loom having means for stopping the weaving function thereof, exchanging 25 a full shuttle for a depleted one, and restarting the weaving function consecutively and automatically.

Another object of the invention is to provide a mechanism having means for feeling the shuttles 30 and to bring into operation the shuttle changing and loom control mechanism upon said feeling means encountering a depleted or nearly depleted shuttle.

Another feature of the invention resides in 35 the provision of a weft replenishing mechanism which may be separately constructed and incorporated in a loom of standard design.

A further object is to provide novel means for 40 feeling the shuttles to determine whether they need replacing.

A still further object is to provide improved means for storing full shuttles ready for insertion into the loom.

The invention also contemplates novel and improved means for synchronizing the loom starting and stopping mechanism and the shuttle exchanging mechanism.

Also contemplated are various safety features 50 designed to protect the loom mechanism should a shuttle become inadvertently jammed during the replacing operation.

While the contemplated mechanism may be successfully employed with a single shuttle loom, its greater use will be found with multiple shuttle looms and the invention therefore contemplates

the provision of simple and accurate means for selecting from the shuttle storing means a shuttle having the same type of yarn as had the one which it is to replace.

In the accompanying drawings, a mechanism of the contemplated character has been disclosed in its preferred embodiment; as the following specification, based on these drawings, progresses, the foregoing and many other objects, advantages, and features of the invention will become more clearly apparent.

In the drawings:—

Fig. 1 is a front view of the mechanism contemplated in this invention as incorporated on a loom of standard design, the weaving instrumentalities of the loom being omitted and the loom being foreshortened.

Fig. 2 is a side view of the mechanism as seen from the left of Fig. 1.

Fig. 3 is a top plan view of a shuttle storing means as employed in the present invention.

Fig. 4 is a front view thereof.

Fig. 5 is a top plan view of a shuttle receiving box carried on the lay at the left of the machine.

Fig. 6 is an enlarged cross sectional view taken 25 through the receiving box and shuttle storing means in one of their cooperating positions.

Fig. 7 is a top plan view of a transmission box employed in the mechanism.

Fig. 8 is a side view of said box with the front 30 side wall removed.

Fig. 9 is a detail sectional view as taken on the line 9—9 of Fig. 7.

Fig. 10 is a front view to an enlarged scale of the yarn feeler means.

The loom in the usual manner is provided with a shipper handle H, a clutch C and a brake B, the latter two being controlled by said handle. Thus, when the loom is started the shipper handle is moved to release the brake and engage the clutch, the reverse being true when the loom is to be stopped.

The mechanism contemplated in the present invention is designed to automatically declutch the machine and set the brake to stop the operation of the loom when a full shuttle is to be exchanged for an empty one; and to automatically reclutch the machine and release the brake after the change has been made so the loom may continue its operative function.

In the usual manner and referring more particularly to Fig. 2, the machine is provided with a lay L which is oscillated through the medium of a crank 25 on a crankshaft 26 by means of a connecting link or links 27. The previously 55

mentioned clutch and brake, control the shaft 26 and thus the operation of the loom. In timed relation with the crankshaft 26, the loom is provided with a camshaft 28, the present ratio being 5 two revolutions of the crankshaft for each revolution of the camshaft.

On the camshaft 28 there is provided a cam 29 having a projection 30 and a slightly depressed portion 31 on the periphery thereof. Engaged 10 with said cam there is one arm 32 of a bell-crank lever pivoted at 33 and carrying on its other arm 34, a dog 35 which is provided with a bifurcated free end 36. To an intermediate portion of the dog 35 there is preferably connected a rod 15 37 which is moved by the floating core of a solenoid 38. Thus as seen from Fig. 2 the cam 29, through the medium of the projection 30 will cause oscillation of the mentioned bell crank lever and hence to and fro movement of the dog 35. When the solenoid core is in the low or 20 deenergized position the bifurcation 36 will pass beneath, and therefore, out of engagement with lug 39 carried by a shift rod 40 which is arranged to have connection through the medium of a rod 41, with the shipper handle. Similarly, it 25 can be seen that when the solenoid core is in the high or energized position the mentioned bifurcation will engage said lug 39 to shift the rods 40 and 41 and thus move the shipper handle H to set the brake and declutch the machine. The 30 above, is therefore, a cam controlled means for stopping the operation of the loom. The means for energizing the solenoid will be later described.

It is desired in the present instance when the 35 loom is brought to a stop in its operation, to set in motion mechanism for effecting the exchange for an empty shuttle of a full one so the loom may continue its weaving operation. For this purpose there is provided a transmission box 42 in 40 which are located parallel shafts 43, 44. On the former there is loosely mounted a sprocket 45 connected as by means of a chain 46 to a sprocket 47 on the camshaft 26. Carried with the sprocket and also free of the shaft 43 there is provided 45 a pinion 48 in mesh with a gear 49 mounted for rotation on the shaft 44. Since both the pinion 48 and the shaft 49 are freely mounted on their respective shafts, the mechanism in the transmission box 42 will remain at rest during the operation of the loom.

The mentioned transmission mechanism best shown in Figs. 7 and 8, will be set in motion when the bifurcation 36 on the dog 35 engages the lug 39. This is accomplished by the shift 50 rod 40 which carries a pivoted pawl 50 engaged with a rock lever 51 in the form of a bell crank pivoted at 52 and having connection through the medium of a link 53 with a lever 54 mounted on a shaft 55 journalled in the transmission box 42. 55 Upon the shaft 55 there is also mounted a control lever 56, the free end of which is arranged to engage the end 57 of a lock motion lever 58. This latter lever is pivotally mounted upon a member 59 keyed at 60 to the shaft 44 and arranged alongside of the gear 49.

The end of the lock motion lever 58 opposite to the stop end is provided with a pin or the like 61 and the gear 49 is provided with a plurality of holes or seats 62 which are adapted to 70 receive the pin 61 in a manner later set forth. A spring 63 is arranged between lock motion lever 58 and the member 59 to tend to urge the pin 61 into one of the holes 62. Normally, however, the free end of the lever 56 engages the stop end 75 57 of the lock motion lever to hold said pin out of

engagement with the holes in the gear 49. This is clearly seen in Figs. 7 and 8.

When the pawl 50 is moved to rock the rock lever 51, the control lever 56 is moved out of engagement with the mentioned stop end of the 5 lock motion lever permitting the spring 63 to rock the last-mentioned lever about its pivot and to cause the pin 61 to seek and enter the first of the holes 62 which it may find as the gear 49 rotates. In this manner, the rotation of the gear 49 is 10 imparted to the shaft 44.

A preferred manner of preventing endwise movement on the shaft 44 of the gear 49 is shown in Fig. 9 wherein one or more pins 64 are driven through the hub 65 on the gear 49 and into engagement with a circumferential groove 66 in the shaft 44.

Upon the shaft 44 there is provided a cam 67 and engaged with said cam there is provided a lever 68 mounted on the shaft 43. The free end 20 of the lever 68 is connected by means of a rod 69 to an arm 70 on the movable front wall 71 of a shuttle box 72. Hence, the engagement of said lever 68 with the high point of said cam will cause, when the shaft 44 is rotated, said lever to 25 be depressed to open the box 72 by moving the front wall 71 outward and upward around its pivot 73 as shown in Fig. 6.

Substantially simultaneously with the opening of the box 72, means for ejecting a shuttle from 30 said box is brought into operation. The shuttle ejector 74 is moved by a lever 75 through a rod connection 76, said latter being provided with a collar 77 engaged by an abutment 78 carried by the rod 69. A slight amount of free play is 35 provided between the collar 77 and the abutment 78 so that the front wall 71 of the box opens in advance of the actuation of the ejector 74. The return movement of the front wall 71 and the ejector is effected through the medium of the 40 respective springs 79 and 79a. (Figs. 5 and 6).

The ejector 74 dislodges a shuttle in the box 72 which then falls in a receiving box 121, being guided by a leather apron 122 or the like.

To further complete the description of the box 45 72, means are provided as a check for the picker 50 stick P, said means comprising a springcheck such as is generally shown at 80.

Upon the shaft 44, there is provided another cam 81 with which is engaged a lever 82 also 55 mounted on the shaft 43. This cam and lever are designed to actuate the mechanism for providing a full shuttle for insertion into the box 72 after an empty one has been ejected from said box. To this end a shuttle magazine 83 is provided and in the present instance comprises a 60 magazine having two compartments 84 and 85, each of which is arranged to support shuttles in stacked relation, the lowermost shuttle of each stack being respectively supported upon the in-reaching ends 86 and 87 of bell crank levers 88-88a and 89-89a.

The lever 89 is provided with a sleeve 90 having an arm 91 affixed thereto and the lever 89a is similarly provided with a sleeve 90a having an 65 arm 91a affixed thereto. A link 92 connects the free ends of the arms 91 and 91a.

The arm 88 is provided with a shaft 93 projecting through the sleeve 90 and has affixed thereon an arm 94. In a like manner, the lever 70 88a is provided with a shaft 93a having a lever portion 94a. The free ends of the levers or arms 94, 94a, are connected as by the link 95.

The arm 91 or the sleeve 90 may have affixed thereto an arm 96 substantially at right angles to 75

the arm 91 and in a somewhat similar manner the shaft 93 may be bent to form an arm 97 disposed at right angles to the arm 94.

Each of the arms 96, 97 are respectively connected to links 98 and 99 which in turn are connected to the ends of the respective levers 100 and 101. These latter levers are mounted for separate rotation upon a common axis, such as shown at 102.

10 The lever 100 is provided with a down-reaching portion terminating in a lateral extension 103 and the lever 101 is similarly provided with a lateral extension 104, the former being disposed below the latter.

15 The laterally extending arms 103, 104 are arranged to be selectively engaged by a projection, stud or the like 105 carried by the upper end of a rod 106 pivoted at 107 at its lower end to an arm 108 mounted at 109 on the machine. The arm 20 108 is carried on the left-hand side of the machine as viewed from the front and its mounting shaft 109 is extended along the front of the machine to mount a lever 110 which is disposed at the right-hand side of the machine, said latter 25 lever being connected as by means of a link 111 to the vibrator arm 112 which is employed to move the box rod 113 as will be hereinafter described.

From the above it may be seen that the vertical 30 position of the stud 105 and the vertical position of the box rod 113 are synchronized and depend on the vibrator mechanism (not shown) which forms part of the loom. Hence, when the stud is in the high position, movement thereof will cause the ends 86 of the levers 88, 88a to be withdrawn so that a shuttle supported on these ends in the compartment 84 may fall upon a shuttle carrier 114; when said stud is in its low position in engagement with the lateral extension 35 103, the ends 87 of the levers 88, 88a will be withdrawn to drop a shuttle from the compartment 85 onto said shuttle carrier 114. The mentioned rod 106, which is vertically moved as above described, is also adapted to be moved in a plane to rock whichever extending arm 103—40 104 opposite which the stud 105 is disposed. In this manner a shuttle from either selected compartment 84—85 is dropped onto the shuttle carrier 114. This lateral motion of the rod 106 will be later described.

50 The shuttle carrier 114 is carried on the end of a lever 115 pivoted at 116 to the machine frame and intermediate its length at 117, said lever is connected to a link 118. In the present instance it is preferred that this connection be readily disengaged should the lever be accidentally halted in its movement as for instance by a shuttle becoming jammed during removal from the magazine. For this purpose the link 118 is provided 55 with a hinged portion 119 spring tensioned as at 120 to engage the connection stud 117 between itself and the link 118.

Since the link is connected to the mentioned lever 82, which through the medium of the cam 60 81, moves the lever 115, should said latter lever be halted by a jammed shuttle, the described disengageable connection will function to free the lever from control of the cam 81.

The lever 115 is adapted to be first moved in a 70 direction towards the front of the loom so it may engage against the rod 106 to impart to said rod the above-mentioned second motion. The cam 81 is formed with a depression as shown in the upper portion thereof (Fig. 8) so the lever 75 82 may transmit this motion to said lever 115

through the medium of the link 118. After a shuttle is dropped upon the shuttle carrier 114 as above set forth, the lever 115 is moved in a direction towards the rear of the loom by the high rise on said cam 81 to deposit said shuttle in the 85 shuttle box 72. The lever 115 is now adapted to return to its position being urged in that direction by the spring 115a under control of the cam 81. A spring 106a is also provided to hold the stud 105 on the rod 106 from engagement with the lever extensions 103—104 except when moved thereagainst by the lever 115.

From the foregoing it can be seen that during a revolution of the shaft 44, the cam 81 thereon, will cause the lever 115 to perform one complete 15 oscillation to transfer a shuttle from the magazine to the empty and open shuttle box 72, the selection between the shuttles in the compartments 84 and 85 of the magazine being made by the mentioned vibrator mechanism through the 20 medium of the levers 108 and 110, and the rod 106.

The lever 82 is yieldingly connected to the link 118 as an added safety to permit said lever to be moved by its cam should connecting portions become jammed. Thus, should the link 118 be held 25 from movement by a failure of a proper exchange of a full shuttle for an empty one, the lever 82 will be able to move by compressing the spring 123. In this manner breakage in the mechanism is obviated. The spring 123 is of sufficient rigidity to 30 afford positive movement of the link 118 by the lever 82, said spring yielding to the movement of said lever only under the above-mentioned abnormal conditions.

After the exchange of shuttles is made, it is 35 desired to restart the operation of the loom, i. e., to release the brake and engage the clutch. For this purpose the shaft 44 is provided with a third cam 124 having engagement with a lever 125 which, at its upper end is connected to a link 40 126 engaged with the shipper handle H. The cam 124 is designed, after the shuttle exchange has been made, to move the shipper handle in the direction to release the brake and engage the clutch. Thus the loom will restart its operation. 45

The means for determining when the quill or bobbin of a shuttle is empty of yarn or nearly so and which energizes the solenoid 38 which operates to set into motion the mechanism for performing the above described shuttle replenishing 50 mechanism, will now be described.

In the usual manner the loom at its right hand side, as shown in Fig. 1 is provided with a shuttle box 127, which in the present instance is formed with two horizontally disposed box compartments 55 128 and 129. This box is arranged as a continuation of the race R of the lay L and it is from this box that a shuttle is projected along the race to the receiving box 72 at the left of the machine to lay a weft thread in relation to the warp ends 60 and then reprojected from said receiving box 72 back to the shuttle box to lay another weft thread.

Depending on the type of fabric to be woven, the mentioned vibrator mechanism through the 65 medium of the arm 112, moves the shuttle rod 113 to shift the shuttle box 127 to the selected compartment 128 or 129 aligned with the race of the lay. As shown in Fig. 1, the lower compartment 129 is so aligned for the projection of a 70 shuttle therefrom along the lay. This movement of the shuttle box by the rod 113 is thus synchronized with the movement of the rod 106 which carries the selector pin 105. Thus when the lower compartment 129 is aligned with the 75

- race, the pin 105 is adapted to engage the lower arm 103 of the releasing mechanism in the magazine compartment 84, (Fig. 4,) and when the upper compartment 128 is aligned with the race, said pin 105 is adapted to engage the upper arm 104 of the releasing mechanism in the magazine compartment 85.

In relation to the shuttle box there is arranged a pair of feelers 130 and 131, the former being adapted to be contacted by the quill of a shuttle in the upper compartment 128 and the latter by the quill of a shuttle in the lower compartment 129.

Each feeler comprises a vertically disposed plate 132, fixedly but adjustably carried at 133 by the lay. Each plate 132 is formed with curved lip portion 134 having a slot 135, said lip portion being formed on the ends of the plates 132 nearest the quills. The opposite end of each plate is formed with a flange 136 and provided with a hole for the passage therethrough of a stem 137 of a feeler member 138 which is engaged in the slot 135. Each feeler member 138 is provided at its end with a plurality of slits, serrations, 25 knurls, or the like 139, these ends being adapted to feel or engage against the yarn on the quills by means of compression springs 140 disposed between abutments on the feeler members and the flanges 136.

30 It is apparent from the above that when the shuttle box is moved to bring a yarn covered quill into contact with a feeler member, that member will be moved in a straight line against its spring since the mentioned slits 139 will have effective contact with the yarn on that quill.

When the yarn on a quill has become depleted the quill will be exposed to contact by the feeler member. Now, when the feeler member is urged back, it will slide along the smooth surface of the 40 quill and thus become cocked as shown in Fig. 10. In this condition, it will come in contact with a contact member 142 carried by the plate 132 but insulated therefrom. An electrical connection 143 is made between the feelers and the 45 solenoid 38 and when the mentioned contact is made said solenoid is energized as previously described.

In brief the operation of the machine is as follows:—

50 The shuttles in the shuttle box are selectively projected back and forth along the lay to provide the weft threads for the fabric woven by the loom. When a feeler becomes cocked to close the solenoid circuit, the cam 29 through its bell crank 55 lever 32—34 will urge the bifurcation 36 to engage the lug 39 on the shift rod 40 to set the brake B and release the clutch C thus stopping the weaving function of the loom. Simultaneously, the dog 50 will rock the lever 51 which, through 60 its connections with the control lever 56, will cause the lock motion lever to couple the shaft 44 with the driving train operated by the crank-shaft 26. The cams 67, 81 and 124 will then make one complete revolution. The control lever 65 56 will resume its initial vertical position in the path of the end 57 of the stop motion lever 58 when the bell crank 32 rides off the high point 30 of the cam 29. This occurs during the rotation of the cam shaft 44. Thus, at the end of one 70 revolution, the stop motion lever 58 will be rocked by the reengagement between its end 57 and the control lever 56 to withdraw the pin 61 from engagement with the hole 62 in the gear 49. In this manner the cam shaft is stopped and the 75 shuttle changing mechanism comes to rest.

During the cycle of movement of the mentioned cams, the depleted shuttle in the box 12 will be ejected and immediately subsequently a full shuttle from the magazine will be fed to the empty box 12, which will then close. At this time, the brake will be released and the clutch reengaged to restart the loom.

While a preferred form of the invention has been disclosed, the type of mechanism which may be employed to carry out the concepts of the invention, may be changed in many ways by skilled persons without departing from the spirit and scope of the invention as claimed. Hence, the prior art rather than the instant disclosure should form the basis of interpretation of the scope of the invention.

What is claimed as new and desired to obtain by Letters Patent is:—

1. In a multicolor weft replenishing loom having a multistack shuttle magazine, the combination with weft replenishing means at an end of the loom, of mechanism for stopping the operation of the loom upon depletion of weft and having a rectilinearly movable shift element connected therewith and carrying an arm, a member having a notched portion in position to be engaged by said arm and movable thereby upon movement of said shift element, unitary one-cycle actuating means arranged at the end of the loom corresponding with the weft replenishing means and including a cam and a control lever for controlling the actuation of the cam, said control lever being connected with the member and actuated thereby, and means operated by said cam for actuating the weft replenishing means.

2. In a multicolor weft replenishing loom having a multicolor magazine for reserve shuttles of different types, the combination with weft replenishing means, of mechanism for stopping the operation of the loom upon the depletion of weft and having a rectilinearly movable shift rod, a pawl pivotally carried by said shift rod, a member having a shoulder engaged by said pawl and movable thereby upon movement of said shift rod, a control lever connected with said member, a lock-motion lever in position for engaging the control lever, a one-revolution shaft having keying connection with the lock-motion lever, a gear freely mounted on said shaft and having circumferentially disposed seats, a pin on the lock-motion lever, means for urging said pin into engagement with one of said seats upon disengagement of the control lever from the lock-motion lever, means for rotating said gear, a cam on said shaft, and means operated by said cam for actuating the weft replenishing means.

3. In a multicolor loom having a multistack shuttle magazine and means for stopping the operation of the loom upon depletion of weft, the combination with weft replenishing means arranged at an end of the loom, of a unitary transmission device arranged at the end of the loom corresponding with the weft replenishing means and having means including an actuating cam for successively replenishing the weft and restarting the operation of the loom, one-cycle operated means for actuating said cam and including a lock-motion lever for controlling the operation of said cam; and means operable on depletion of weft for controlling actuation of the lock-motion lever to provide for rotation of the cam including a shift rod connected with the loom stopping means and having an abutment, a shiftable dog, power means for moving said shiftable dog relative to the shift rod, and means actuated on de-

pletion of weft for moving said shiftable dog into position for engagement with the abutment and for operating the shift rod thereby.

4. In a multicolor loom having means for stopping the operation of the loom upon depletion of weft, the combination with weft replenishing means, of a unitary transmission device having means including an actuating cam for successively replenishing the weft and restarting the operation of the loom, said device including a continually driven shaft and a one-revolution shaft, said cam being carried by said latter shaft, gearing connecting said shafts together and including a gear provided with circumferentially disposed seats, said gear being freely mounted on said one-revolution shaft, a lock-motion lever mounted on said one-revolution shaft for rotation therewith and for rocking movement in a plane transverse to the axis thereof, a pin on said lever in position to engage one of said seats, means for holding said pin out of said engagement during the normal operation of the loom, a shift rod connected with the loom stopping means and having an abutment, a shiftable dog, power means for moving said shiftable dog relative to the shift rod and means operable upon depletion of weft for moving said shiftable dog into position for engaging the abutment and for operating the shift rod thereby to stop the loom

and for releasing said holding means and for engagement of the pin in one of said seats whereby rotation is imparted to said one-revolution shaft and to said cam.

5. In a multicolor shuttle changing loom, the combination with weft replenishing means including a multi-stack shuttle magazine, of mechanism for stopping the operation of the loom upon depletion of weft including a rectilinearly movable shift rod carrying a stop member, a rotatable shaft, a cam on said shaft, a member co-acting with said cam for oscillatory movement thereby, a dog pivotally carried by said member, a solenoid, means for energizing said solenoid upon depletion of weft, a connection between the solenoid and the dog whereby the dog is positioned out of the path of the stop member when the solenoid is deenergized and is positioned in the path of said stop member when the solenoid is energized to impart rectilinear movement to the shift rod for operating the loom stopping mechanism, and means connected with and brought into action by actuation of said stopping mechanism for actuating the weft replenishing means upon stopping of the operation of the loom.

ERNEST A. MORIN.
MORRIS BORNSTEIN.
